UNITED STATES PATENT OFFICE.

ALBERT B. SCHOFIELD, OF NEW YORK, N. Y., ASSIGNOR, BY MESNE ASSIGNMENTS, TO THE CORPORATION TRUST COMPANY, TRUSTEE, OF JERSEY CITY, NEW JERSEY, A CORPORATION OF NEW JERSEY.

SEAL.

No. 873,618.

Specification of Letters Patent.

Patented Dec. 10, 1907.

Application filed August 23, 1905, Serial No. 275,367.

To all whom it may concern:

Be it known that I, ALBERT B. SCHOFIELD, a citizen of the United States, and resident of the borough of Manhattan, in the city and 5 State of New York, have invented a new and useful Improvement in Seals, of which the following is a specification.

My invention relates to seals and more particularly to that type of seal in which the 10 shackle is formed of heavy wire and the body of some suitable pliable metal as, for example, lead.

The object is to provide a seal which shall be effective and inexpensive.

15 A practical embodiment of my invention is represented in the accompanying drawings, in which

Figure 1 is a view of the seal in side elevation showing the shackle in position to be inserted in the body, Fig. 2 is a transverse section through the body in the plane of the line A—A of Fig. 1, Fig. 3 is a longitudinal section through the body in the plane of the line B—B of Fig. 2, Fig. 4 is a bottom plan 25 view, and Fig. 5 is a transverse section through the body, showing the latter gripped between the jaws of a press to complete the sealing.

The shackle denoted by 1 is preferably 30 formed of stiff heavy wire and is made in loop form with its ends in position to be sprung toward one another to enter the body of the seal, its extreme ends being provided with outwardly turned portions 2 and 3 for 35 the purposes of catching under an internal shoulder within the body of the seal.

The body of the seal is denoted as a whole by 4. It is provided with sockets 5 and 6 entering it at the end where the shackle is to 40 be inserted, the sockets being shown as separated by a central diaphragm or web 7, which diaphragm or web preferably stops short of the end of the body leaving the two 45 sockets merged into one at the end. At the opposite end the body 4 is provided with 50 sockets 8 and 9 extending inwardly and offset from the line of the sockets 5 and 6, it being the intention that the sockets 8 and 9 shall be off-set from the sockets 5 and 6 just 55 the diameter of the sockets 8 and 9 so as to form a juncture with the sockets 5 and 6 where the one laps past the other and in order to make this juncture of the two sockets 60 wide open for the reception of the ends 2 and 65 3 of the shackle, I make the sockets 8 and 9 half round as clearly shown in Fig. 4, or, in any event, with flattened sides 10 and 11 adjacent to the sockets 5 and 6 respectively. The bottoms of the sockets 8 and 9 form the shoulders 12 and 13 under which the outwardly turned ends 2 and 3 of the shackle 70 catch when the shackle is inserted in the body of the seal.

3 of the shackle, I make the sockets 8 and 9 55 half round as clearly shown in Fig. 4, or, in any event, with flattened sides 10 and 11 adjacent to the sockets 5 and 6 respectively. The bottoms of the sockets 8 and 9 form the shoulders 12 and 13 under which the outwardly turned ends 2 and 3 of the shackle 60 catch when the shackle is inserted in the body of the seal.

The body of the seal is preferably made with its opposite edges rounded, as shown in 65 the transverse sections, Figs. 2 and 4, or in any event with its corners cut away and it is further the intention to make the opposite edges of the body parallel as distinguished from the tapered form which has heretofore 70 been common.

By making sockets at the opposite ends of the body and so locating them and forming them that they join within the body of the seal, I provide for drawing the cores in right 75 lines in the casting of the bodies and thus materially lessen the expense of casting while maintaining the hooked or outwardly turned ends 2 and 3 of the shackle completely embedded in the body thereby preventing any 80 liability of their becoming twisted and the seal thereby weakened.

The rounding or cutting of the corners of the body serves a very useful purpose in seating the body in the jaw of a press as, for 85 instance, in the jaw 14 of the press represented in Fig. 5, and centering the body during the action of the plunger 15 which serves to close the body tightly around the ends of the shackle completely embedding the latter 90 within the body and leaving the proper impress on the seal. By making the opposite edges of the seal parallel, a minimum amount of metal is required to produce the necessary strength and the cost of casting is 95 reduced.

What I claim is:—

1. A seal comprising a shackle having its ends turned to form retaining hooks or shoulders and a body of soft metal having 100 shackle receiving sockets entering it at one end and sockets entering the said body at the opposite end, the said last named sockets being off-set from the shackle receiving sockets and spaced from the sides of the body in 105 position to join the shackle receiving sockets within the body of the seal, whereby the locking ends of the shackle may be com-

pletely housed within the body of the seal when the latter is pressed.

2. A seal comprising a shackle having outwardly turned ends for retaining it and a soft metal body provided with shackle receiving sockets in one end and flat sided sockets at the opposite end offset from the shackle receiving sockets and arranged to overlap and connect with the shackle receiving sockets.
- 5 3. A seal comprising a shackle having hooked retaining ends and a soft metal body having its opposite edges parallel and rounded, the said body being provided with shackle receiving sockets at one end and

with sockets at the opposite ends spaced 15 from the sides of the body and off-set from the shackle receiving sockets the said sockets being arranged to lap past the shackle receiving sockets and communicate therewith.

In testimony, that I claim the foregoing 20 as my invention, I have signed my name in presence of two witnesses, this sixteenth day of August, 1905.

ALBERT B. SCHOFIELD.
